UNITED STATES PATENT OFFICE

WILLIAM E. HARDING, OF INDIANAPOLIS, INDIANA, ASSIGNOR TO TELETYPE CORPORATION, OF CHICAGO, ILLINOIS, A CORPORATION OF DELAWARE

TELEGRAPH SENDING AND WRITING INSTRUMENT

Application filed June 19, 1926, Serial No. 117,082. Renewed February 6, 1928.

My invention relates to telegraph sending and receiving instrumentalities; and more particularly to mechanisms of this kind in which key board operated sending devices, 5 and printing telegraph receiving instruments are used; and consists substantially in the construction, combination and arrangement of parts hereinafter set forth and pointed out more particularly in the claims.

10 An object of my invention is to provide in connection with such sending instrument, an improvement to prevent the inadvertent writing of one line upon another in the corresponding receiving instrument.

15 It is a primary object of my invention to provide a safety means for sending instruments of the class in which a certain key serves as the line feed key, and another key serves as the carriage return key, said safety means acting to automatically lock the remaining keys from operation when the carriage return key is operated; and a means 20 acting to automatically unlock said remaining keys with the operating of the line feed key; for preventing the operator from writing a new line before the line feed key has 25 also been operated.

It is a further object to provide a means to manually engage or disengage such locking 30 means independently of the automatic manipulation of same, when desired.

In order to thus automatically lock and unlock the character keys in the finger board 35 of a sending telegraph instrument, I have provided guide mounted ledge means below said keys, adapted to be moved, into or out of the path of same, for preventing or allowing operation thereof; and a connection between said ledges, whereby they may be 40 moved in unison to locking or unlocking position.

It is a further object to provide a slanting surface on said connection, under the carriage return key, whereby the normal carriage return movement of same will move 45 said ledges to locking position, by the cam action of said surface, in contact with said carriage return key; and a corresponding slanting surface on said connection, under 50 the line feed key, whereby normal line feed-

ing movement of same will move said ledges to unlocking position; whereby the operator is prevented from writing a new line until the line feed key has been operated.

It is also an object to provide an accessible 55 means as a part of the key board to manually shift said ledges to locking and unlocking position, as desired, independently of the carriage return or line feed keys.

It is a highly important object of my invention to provide an electro-magnet means 60 for shifting said ledges and connecting means, said means having contacts for closing the energizing circuit of same, which are brought together by striking the carriage return key; and the circuit being correspondingly broken by the line feed key.

The above and other objects are attained 65 by the structure illustrated in the accompanying drawings, in which:

Figure 1 is a fragmentary plan view of a telegraph sending instrument with which my invention is embodied; Fig. 2 is a front fragmentary view of Fig. 1; Fig. 3 is a sectional view taken in the proximity of line 70 75 3-3 of Fig. 2; Fig. 4 is a wiring diagram showing the "hook-up" for my electro-magnet key bar locking means, and also indicates mechanical structure of some of the parts; and Fig. 5 illustrates the electrical 80 diagram of the telegraph sending instrument to which my invention has been conveniently added.

Similar characters of reference designate 85 similar parts thruout the several views. Referring to Figure 1, the numeral 1 designates the main frame of the telegraph sending instrument, which is operated principally by means of the character writing keys 2.

As is understood by those familiar with 90 the art, key board operated printing telegraph outfits are of at least two distinct kinds. In the kind shown, manipulation of the character keys 2 produces different sets of perforations along in the continuously 95 fed telegraph tape 3, of correspondingly different code sending values, as will be understood.

Said tape is then run thru a code sending 100 mechanism (not shown) which transmits

electrical impulses of different predetermined values, thru current carrying wires, to a corresponding telegraph writing instrument, at the receiving station, and actuates the writing mechanism of same, usually in regular page formation.

In addition, however, to such tape using telegraph instruments, there is also commonly in use, key board operated sending instruments in connection with which, manipulation of the keys, transmits electrical impulses directly over the regular telegraph lines to corresponding telegraph writing instruments, which, by means of electro-magnets thus brought into play in the writing instrument, causes same to write directly upon the page, by which provision, the use of the perforated tape is not required.

In view of the fact that my improvements 20 may be used on either the tape using or direct sending telegraph instruments, of the finger board type, it is thought sufficient to arbitrarily illustrate my invention in connection with the tape using sending mechanism, it 25 being understood that it may be readily applied to the direct sending, and other similar apparatus.

In the particular sending instrument shown, the writing keys 2 extend rearwardly 30 thru a clearance opening 4 in the front wall of the main frame 1, and are pivoted within said frame near the rear wall 5 thereof. The "bracket" shaped levers 6 are likewise pivoted at points lower than said keys toward the left 35 and right end walls 7 and 8 of said frame. Said levers are of the reclining "printing bracket" shape, the normally vertical spans 9, of which, are disposed transversely along under said keys, in horizontal position, and 40 form the power ends of said levers. Said "bracket" shaped levers are arranged successively in graduated sizes in relation to each other, and are nested together, one within the other, and pivoted in common at 45 their left and right ends 10 and 11, respectively, by means of the two pivot pins 12 and 13, respectively, which are secured thru corresponding parts of the frame 1.

The selecting combs 14 are formed downwardly on the keys 2, each comb being constructed so as to make contact with a different combination of the lever spans 9.

The angle levers, 15, 16, 17, 18, 19 and 20 stand in horizontal planes, and being arranged one over the other in order as stated are adapted to be pivoted upon a common vertical pivot 21, which is supported thru the floor 22 of the frame 1. The power ends 23, 24, 25, 26, 27 and 28 of said angle levers 50 are of graduated lengths, they being shorter in downward succession. In accordance with this arrangement, the corresponding left ends 10 of the bracket levers 6 are extended upwardly from the pivot pin 12 thru the clearance opening 29 of the frame floor 22, and

being of correspondingly graduated lengths are conveniently pivoted to different ones of said power ends, the longer or outer bracket lever end, being pivoted to the longer or upper power end 28, and the short or inner bracket lever end being pivoted to the shorter or lower power end 23, etc. 70

The load ends 30, 31, 32, 33, 34 and 35 of the angle levers 15, 16, 17, 18, 19 and 20, respectively, are disposed at substantially right angled formation with the power ends of said angle levers, and engage adjacent ends of the horizontal trigger arms 36, 37, 38, 39, 40 and 41 at substantially right angles thereto, in free working relation therewith by 80 which arrangement said angle levers serve to shift said trigger arms longitudinally. 75

A set of five independent tape perforating punches 42 are horizontally guided thru the stationary head 43, being arranged in a vertical row in relation to each other and transversely to said trigger arms. The hammers 44 carried one each by said trigger arms face, one toward each of said punches, when said triggers are held in working position, by 90 means of the bracket levers 6 thru the aforesaid angle levers. 85

It will be obvious that operation of the character writing keys 2, will cause corresponding oscillation of the said angle levers, 95 move the respective trigger arms longitudinally, and shift the said hammers out of line with the respective punches 42, and thus be positioned to miss same by manipulation of the aforesaid angle levers. The other ends 100 of said punches are positioned to directly face the telegraph tape 3 as it is fed from the roll 45 past the roller 46 and thence across the head 43; from whence it is fed thru the guide 47, as will be understood. 105

An electro-magnet operated hammer means 48 is mounted on the frame floor 22, having a driving bit 49 adapted to strike all of the aforesaid trigger arms simultaneously and directly, on the opposite side thereof from 110 the punches 42.

The selecting combs 14 of the character writing keys 2 are so constructed that operation of any of said character keys will cause oscillation of the angle lever 18, which carries the contact point means 50; and when the said angle lever 18 is at the end of its stroke, said contact means is carried against the stationary contact point 51, and thereby completes the circuit for the electro-magnet hammer means 48, which drives the aforesaid trigger arms toward the punches 42. It will be understood that the hammers 44 of the aforesaid trigger arms, which happen to have been left in line with the angle levers, unaffected by the particular selecting comb 14, brought into play by the operator, will be forced by the driving bit 49, to punch a corresponding set of code sending holes in the tape 3, which is then fed along past said punches ready to 130

be perforated again and is thus perforated ready to be used by the impulse sending mechanism (not shown).

I am aware that the mechanisms such as 5 described in the foregoing detailed explanations are neither new nor novel, but are now in somewhat common use. Nevertheless it is thought appropriate to describe somewhat completely the old structure which I have 10 chosen as a means of setting forth the use of my particular improvements, in order to 15 amply establish the operativeness thereof.

The tape thus perforated is run thru said direct impulse sending mechanism from 15 which different sets of impulses are transmitted over the regular telegraph lines to a page writing telegraph receiving instrument (not shown), to which the different sets of impulses cause different characters to be written 20 on the platen of said receiving instrument in page formation.

When a certain number of characters and spaces have been thus printed to a line, it is necessary to return the platen carriage to the 25 beginning position for a new line. For this purpose one of the keys 52 is designated as the carriage return key, the pressing of which causes to be punched a certain combination of perforations in the tape 3, which actuates 30 the carriage returning mechanism of the receiving instrument and causes same to be returned to line starting position.

Before beginning to write a new line, however, it is, of course, necessary to rotate the 35 platen (not shown) in the receiving instrument to avoid writing the new line on the preceding line, as is understood in connection with all page writing mechanism, such as type writers. For this purpose, I have also designated one of the keys 53 as the line feed key, the pressing of which causes to be punched a certain other combination of perforations in the tape 3, and which causes operation 40 of the platen rotating mechanism of said receiving instrument, and causes same to be suitably rotated for beginning a new line.

One of the most common mistakes in the operation of page telegraph sending instruments of this character, lies in the fact that 50 the operator very often forgets to press the line feed key before beginning a new line, in which instance, the new line is written right over the previously written line, rendering them both unreadable. It is principally to prevent such mistakes as this, that 55 I have made the improvements which constitute my invention; my object being to automatically lock the character writing keys 2 against operation when the carriage return 60 key 52 is pressed; so that it is impossible to begin writing the new line until the line feed key has also been pressed, the operation of same serving to automatically unlock the character writing keys.

65 As before indicated, entrance of the keys

2, 52 and 53 into the interior of the main frame 1 is made thru the front wall of said frame, the clearance opening 4 being provided for that purpose. Said opening is substantially closed, however, by means of the vertical plate 54, which has vertical slots 55, one each, to guide the said keys in corresponding vertical planes.

Along the lower front surface of said plate, parallel thereto, my new and novel plate-like lock bar 56 is provided in slideable relation thereto, which has notches 57 for giving clearance to said keys when pressed downward in working movement. Said lock bar is conveniently held in place by means of the headed screws 58 which slidably engage the horizontal slots 59 of same, and thread into the plate 54. The slots 59 being longitudinally arranged in respect to said lock bar, allow longitudinal movement of same. Ledges 60 are formed between the notches 57 adjacent the character keys 2 which may be shifted in unison with said lock bar, one each under said character keys, and thus prevent operation of same, as shown in Fig. 2.

The ledge 61 is likewise formed on the lock bar 56 adjacent the carriage return key 52. This ledge, however, has an upper surface 62 which slants downwardly to the right, and which stands directly under said carriage return key in the working path thereof, when said lock bar is in key unlocking position, which upon striking said surface it serves to cam said lock bar to the left and likewise 95 shift the ledges 60 under the character keys 2, thereby locking the same against operation.

Another cam acting ledge 63 is in like manner formed on the lock bar 56 adjacent the line feed key 53, which stands directly under said line feed key in the working path thereof, when said lock bar is in key locking position. The surface 64 of the ledge 63 slants oppositely to the surface 62, and serves to cam the lock bar to the right, to unlocking position and the ledges 60 correspondingly out from under said character keys, and thereby unlock same so that they may be freely operated.

It will therefore be understood that normal operation of the carriage return key 52 will automatically lock the character keys 2 against operation, until the line feed key 53 has been also operated, by which arrangement it will be impossible for the operator to make the very common error of starting to write a new line before the platen in the receiving instrument has been properly rotated.

Independently of the above indicated mechanical provisions for operating the lock bar, I have also provided an electro-magnet means for shifting same automatically, upon operation of said carriage return key, and a spring means for returning same to unlocked

position upon operation of said line feed key. It is understood that my invention is operable with either or both the mechanical or electro-magnet means.

- 5 Said electro-magnet means is constructed by supporting an electro-magnet 65 on the main frame 1, in fixed manner, the poles 66 of which electro-magnet, face codirectionally with the unlocking movement of the lock bar 56. An armature 67 oscillates upon the pivot 68 in a plane parallel to said lock bar, within close magnetic range of said poles, and its free end is coupled to said lock bar, by an adjustable bolt which engages said armature 10 and also the bracket 69 of said locking bar, in such manner that said lock bar may be shifted to locked position by said armature when same is attracted by said electro-magnet.
- 15 20 As a means for operating said electro-magnet in conjunction with the carriage return key 52 and the line feed key 53, I have secured the insulating bracket 70 to the main frame 1, approximately under a halfway point between said carriage return key and said line feed key. Upwardly from said insulating bracket, the brush 71 extends and bends sideways under the said carriage return key, by which arrangement, normal 25 downward working movement will bring same into contact with the bent portion of said brush, and by the resulting cam action, spring same sideways, correspondingly springing the circuit carrying spring 72, which stands 30 approximately parallel to the brush 71, being located thereonto by means of the insulating spacers 73 and 74. In like manner, a fixed contact support 75 is located onto said spring on the opposite side from said brush by means 35 of the insulating spacer 76 by which arrangement, downward movement of the carriage return key 52 will spring the circuit carrying spring 72 with the brush 71, and bring said spring against the contact 77 of the contact support 75, which completes the circuit 40 between the electro-magnet 65 and the current source 78, the current being transmitted in order as stated; from said source thru the conductor 79 to the junction 80, thence thru 45 the conductor 81 to the contact support 75, the contact 77 and to the spring 72, thence thru the conductor 82, the juncture 83 and conductor 84, thence thru juncture 85 and conductor 86 to the electro-magnet coil 87, 50 from whence the current is then directed by the conductor 88, the juncture 89, and the conductor 90 to the manual switch 91, and thence to said electrical source. Upon thus 55 completing said circuit, the electro-magnet 65 is energized and draws the armature 67 toward same, and likewise the lock bar 56 to key locking position with the same effect as if cammed to locking position, by means 60 of the slanting surface 62 by the carriage return key 52 as described above.

Upwardly from the insulating bracket 70, the brush 92 also extends and bends sideways under the line feed key 53, by which arrangement normal downward working movement will bring same into contact with the bent portion of said brush, and by the resulting cam action, spring same sideways correspondingly springing the circuit carrying spring 93, being located thereonto by means of the insulating spacers 94 and 95. 70 In like manner a fixed contact support 96 is located onto said brush, by means of the insulating spacer 97, by which arrangement downward movement of the line feed key 53 will spring the circuit carrying spring 93 with the brush 92, and bring said spring against the contact 98 of the contact support 96, which completes a shunt circuit for the current source 78 by way of the conductor 79, the juncture 80, the conductor 99, the conductor carried contact 100, the stationary contact 101, the conductor 102, the juncture 85, the conductor 84, the juncture 83, the conductor 103, the contact support 96, the contact 98, the contact spring 93, the conductor 104, the juncture 89, and the conductor 90 to the switch 91 and thence to said current source, by which the electric magnet 65 being no longer energized, permits the contraction coil spring 105, which is tensioned 90 between the lock bar ear 106 and a hole 107 in the frame 1 on the opposite side of said ear from said electro-magnet by the slip pin 108, to draw same from attracted position and at the same time, shift the lock bar 56 to 100 unlocking position. It is understood, however, that said slip pin 108 is normally withdrawn by the operator, to render the spring 105 inactive, when depending upon the slanting surfaces 62 and 64 to operate the lock bar 56, by which, action of said spring is avoided as would be desired. An extensive knurled head is provided on said slip pin, acting as a handle for readily inserting or withdrawing same.

110 The contact screw 100 is secured in threaded relation with the armature 67, the nose of said screw facing the contact point 101 which is thus supported by means of the bracket 109 of the electro-magnet 65. Said contact screw is adapted to be drawn against said contact point, when said armature is energized thru the above described operation of the carriage return key 52, and completes a self locking circuit collateral with 115 the circuit closed by said return key, the current being carried from the source 78 by the conductor 79 to the juncture 80, thence thru the conductor 99, the contact screw 100, the contact 101, the conductor 102, the juncture 120 85, the conductor 86, the electro-magnet coil 87, the conductor 88, the juncture 89, the conductor 90, and the switch 91 to said source. It will be apparent that after the carriage return key 52 is released by the operator, and 130

- the circuit thru the contact 77 is automatically broken, the electro-magnet 65 will then be energized by the above described collateral locking circuit, and the lock bar 56, will be thus held in locking position after said carriage return key is released. Operation of the line feed key 53 however will cross circuit the current source 78 in shunt relation with said locking circuit and thereby render the electro-magnet 65 inactive, whereupon the lock bar 56 will then be drawn to unlocking position by means of the spring 105, by which a continued use of current from the source 78 is avoided.
- Directly on the opposite side of the tape 3 from the punches 42, the die 110 is positioned with cutting holes to receive said punches, which function with same in perforating said tape, as will be understood by those familiar with the art. The space between the punch head 43 and said die is suitable to snugly guide the tape 3 as it travels past the punches 42.
- The tape 3 is drawn from the roll 45 by means of the tape sprocket 111, which is pivoted thru the frame floor 22, and being pivoted on the opposite side of the punch guide 43 from said roll 45 serves at the same time to draw said tape along said punches, across the cutting face of the die 110. Said die extends to a position of relative tangency with said sprocket and serves to keep the tape in mesh with same, forming the tape guide 47, aforementioned.
- As before stated, the selecting combs 14 of the character writing keys 2 are so constructed, that operation of any of said character keys, will cause oscillation of the angle lever 18. It is therefore obvious that the hammer of the corresponding trigger arm 39 would accordingly be shifted to normal non-punching position upon pressing of any of said character writing keys. I desire, however, to actuate the punch opposite the trigger arm 39 at each stroke of any of the character keys 2. In view of this, an extension 112 is provided on the hammer of the trigger arm 39, which actuates said punch when said trigger arm is shifted to normally non-punching position as compared to the other trigger arms. The extension 112 is therefore adapted to actuate a medial one of the punches 42, and being brought into play at each character key stroke, will correspondingly punch a regular row of holes along a medial line of the tape 3, in line with the sprocket 111, and be adapted to mesh therewith, and pull said tape gradually along as it is thus perforated.
- Between the floor 22 and the sprocket 111 the ratchet wheel 113 is concentrically secured to said sprocket. A hook pawl 114 extends rearwardly from a working position, in respect to the left of said ratchet wheel. Said pawl is pivoted in this position onto the bracket 115 which is formed on the driv-
- ing bit 49 and extends transversely, and to the left, therefrom. By this arrangement it will be understood that the regular strokes of the electro-magnet hammer means 48 will actuate said pawl in longitudinal strokes and thereby actuate the tape sprocket 111 thru the ratchet wheel 113, the contracting coil spring 116 being adapted to keep said pawl swung into contact with said ratchet wheel.
- Directly under the floor 22 the spur gear 117 is concentrically pivoted with the sprocket 111 and the ratchet wheel 113 and is adapted to be rotated integrally therewith. A considerably larger spur gear 118 is disposed in normal meshed relation with the spur gear 117 and is pivoted to the frame floor 22 by means of the pivot 119. Said larger gear carries a crank like pin 120 which serves at each revolution to strike the contact brush 121 and spring same against the contact means 122, being shown about to do so in Fig. 1 and thereby close the circuit of the signal light 123, which is disposed under the apron 124 which extends forwardly from the main frame 1, under the keys 2, 52 and 53; a hole 125 being provided in said apron for observing said light by the operator.
- Now the spur gears 117 and 118 are of such sizes that a revolution of the gear 118 is just completed when a given line quantity of registrations have been punched in the tape 3 by operation of the character keys 2, by which arrangement the brush 121, is actuated whenever a length of tape has been perforated, having a printing value of one line in the receiving instrument. It will therefore be understood that when a predetermined line value length of the tape has been perforated, the light 123 will be illuminated and warn the operator that the carriage return key must be pressed, and also the line feed key. If, however, the operator forgets to operate the line feed key, the character writing keys 2 will be automatically locked against operation, as above explained. It is understood that any other signal means may be provided in place of the light 123. For example, an electrically operated bell, or the equivalent. It is also understood, however, that my invention may operate without any such signal means whatever.
- Referring to the lock bar 56, it is important that the amount of travel to locked or unlocked position should be somewhat definitely predetermined. The working movement of the keys 52 and 53, however, may vary slightly with different conditions or operators. With these facts in view, it is more practical to make the slanting surfaces 62 and 64 of such angle and length that the shifting movement of said lock bar is well completed; at the same time permitting continued movement of said keys without continued movement of said lock bar. For that reason the

said slanting surfaces are ended at their lower terminations to provide just sufficient working length in respect to their cam action against the keys 52 and 53 to accurately shift the locking bar 56 to locking and unlocking positions, allowing the said keys to slide off of said ends and complete their downward strokes without imparting continued shifting movements to said bar. It is understood, however, that the slots 59 of said lock bar are of such length as to properly stop the lock bar movement against the screws 58 in either direction.

Along under the keys 2, within the frame 1, the spring seat bar 126 extends transversely to said keys and is secured to the end walls 7 and 8, by means of the inwardly extending screws 127. Said bar contains holes 128, one being provided under each of the keys 2, and said keys are each provided with downwardly opening notches 129. Hair springs 130 one for each of said keys are exerted between the notches 129 and the corresponding holes 128 by which arrangement said hair springs return said keys to their upper or normal positions shown in Fig. 2 and Fig. 3, after the downward strokes thereof.

Referring to Fig. 5, a wiring diagram is shown, illustrating a conventional hook-up for operating the electro-magnet hammer means 48, in which the current is carried by means of the current supply 131, thru the conductor 132, to the juncture 133, thence thru the conductor 134 to the hammer means 48, thence thru the conductor 135 to the contact point 136 and contact lever 137, and thence thru the conductor 138 to the juncture 139 and thru conductor 140 from whence it is carried to the current source 131. The light 123 is illuminated by current from the source 131 thru the brush 121, when actuated by the pin 120 as before mentioned, when said light is thus illuminated; the current travels from said source thru the conductor 132 to the juncture 133 and thence thru the conductor 141 to the light 123, and thence thru the conductor 142 to the contact 122, the brush 121, the conductor 143, the juncture 139, the conductor 140 to said source. The aforesaid insulating bracket 70 is secured to the inner side of the vertical plate 54 by means of the screw 144 said plate being in turn secured to the frame 1 by means of the screws 145.

The screw 146 engages the contact support 75, the insulating spacer 76, the circuit carrying spring 72, the brush 71, and is securely threaded into said insulating bracket and secures said parts together. In like manner the screw 147 engages the contact support 96, the insulating spacer 97, the circuit carrying spring 93, the brush 92 and is securely threaded into said insulating bracket.

There are some circumstances in which

it is desirable to avoid the locking tendency of said lock bar, and for that reason I have attached an accessible handle 148 to same, by which it may be manually shifted to unlocked or locked position as desired, either cooperatively or independently of the operation of the carriage return key 52 or the line feed key 53.

The electro-magnet 65 may be rendered inactive as desired by opening the manually operated switch 91, it being proper to also render the spring 105 inactive at the same time, by conveniently withdrawing the slip pin 108, under which condition, operation of the lock bar 56 is dependent entirely upon the cam action of the surfaces 62 and 64 against the keys 52 and 53. It is also understood however, that a telegraph sending device may be provided with neither, either or both the cam actuating means or the electro-magnet means of operating said locking bar.

The mechanism is operated thru the spacer key 149 to register the usual spacing values between letters or words on the tape 3.

The contact means 122 and the contact brush 121 are supported by the insulating block 150, which is disposed between, and secured to same by means of the rivet 151. The block 150 is secured to the under surface of the frame floor 22 by means of the screw 152.

For the purpose of stabilizing the locking and unlocking movements of the lock bar 56, I have provided a bowed spring 153, of flat material, the ends of which frictionally embrace said bar under tension of the screw 154 which engages said spring at a medial point thereof and passes thru said bar and engages the key guide bar 54. A slot (not shown) similar to slots 59 is provided in said lock bar to allow ample movement of same. Said bow spring steadies the lock bar movements by the brake effect upon same, prevents dangling of said bar on the screws 58, and also prevents the unintentional movements of same.

The bolt which couples the lock bar bracket 69 with the armature 67, before mentioned, is designated by the numeral 155.

The contact point 51, is adjustably supported integrally on the nose of the screw means 156, said screw means being threaded thru the bracket 157 which is integrally mounted on the frame floor 22. The electro-magnet hammer 48, the punch guide head 43, the die 110, the pivot support for the roller 46, and the pivot 158 of the tape roll 45 are also, all integrally mounted on said frame floor.

Attention is called to the fact that Fig. 4 fragmentarily shows the lock bar 56 in unlocking position while Fig. 2 shows the locking position of same.

While I have illustrated in a general way, certain instrumentalities which may be employed in carrying my invention into effect

it is evident that many modifications may be made in the various details, without departing from the scope of the appended claims, it being understood that my invention is not 5 restricted to the particular forms herein described.

I claim as my invention:

1. In tape telegraph sending instruments having character sending keys, a carriage return key, a line feed key and a means to register sending values on the tape thru operation of such keys; a slidably supported ledge means adapted to be slid under the character writing keys for obstructing same, 15 said ledge means having a cam surface in the working path of the carriage return key, serving to cam said ledge means under said character sending keys, by contact of said carriage return key, whereby the character 20 keys are locked, said ledge means having another cam surface in the working path of the line feed key serving to cam said ledge means from under said character writing keys by contact of said line feed key; whereby operation 25 of the carriage return will lock said character writing keys, and operation of the line feed key will unlock same; to prevent the registration of character values on said tape until the line feed value has been registered on same.

2. In telegraph sending instruments having character sending keys, a carriage return key, and a line feed key; a movably supported ledge means adapted to be moved under the character writing keys for obstructing same; a means serving to move said ledge means under said character sending keys, by operation of said carriage return key, whereby said character sending keys are locked; and another means serving to move said ledge 40 means from under said character writing keys by operation of the line feed key; whereby operation of the carriage return key will lock said character writing keys, and operation of the line feed key will unlock same; to prevent the writing of one line on another.

3. In telegraph sending instruments having character sending keys, a carriage return key, and a line feed key and a means to register sending values on the tape thru operation of such keys; a means to automatically lock the character writing keys, operated by the carriage return key; and a means to automatically unlock same, operated by the line feed key to prevent the receiving instrument from writing one line upon another.

4. In tape telegraph sending instruments having character sending keys, a carriage return key, a line feed key, and a means to register sending values on the tape thru operation of such keys; a slidably supported ledge means adapted to be slid under the character writing keys for locking same; and an electro-magnet, the energizing circuit of 60 which is automatically closed by operation of

the carriage return key, said electro-magnet serving to attract said ledge means to locking position, under said character sending keys, when energized, whereby they are locked against operation; to prevent the registration of character values of said tape after a reading line of values have been registered on said tape.

5. In telegraph sending instruments having character sending keys, a carriage return key, and a line feed key; an electro-magnet means to automatically lock the character writing keys, automatically brought into place by the carriage return key; and a means to automatically unlock same, operated by the line feed key to prevent more than a line value of combined strokes by said character writing keys, without operation of the line feed key.

6. In telegraph sending instruments having a carriage return key means, a line feed key means, and another key means; a movably supported ledge means adapted to be moved under said other key means for obstructing same; a means serving to automatically move said ledge means under said other key means, by operation of said carriage return key means, whereby said other key means are locked; and another means serving to automatically move said ledge 85 means from under said other key means by operation of the line feed key means; whereby operation of the carriage return key means will lock said other key means, and operation of the line feed key means will unlock same.

7. In telegraph sending instruments having a carriage return key means, a line feed key means, and other key means; a movably supported ledge means adapted to be moved under said key means for obstructing same; a means serving to automatically move said ledge means under said other key means, by operation of said carriage return key means, whereby said other key means are locked; and another means serving to automatically move said ledge means from under said other key means by operation of the line feed key means; whereby operation of the carriage return key means will lock said other key means, and operation of the line feed key means will unlock same; to prevent the writing of one line on another.

8. In telegraph sending instruments having character sending keys, a carriage return key, and a line feed key; a movably supported ledge means adapted to be moved under the character writing keys for locking same; a source of electrical current supply; an electro-magnet serving to attract said ledge means to locking position, the energizing circuit of said electro-magnet being automatically closed with said supply by operation of the carriage return key, whereby the character keys are locked; another means 120

tending to move said ledge means to unlock-
ing position in opposition to said electro-
magnet means; a cross circuit means for said
source adapted to be automatically closed by
5 operation of said line feed key, to render said
electro-magnet inactive, whereby operation
of the carriage return key will lock said char-
acter writing keys, and operation of the line
feed key will unlock same; to prevent the
10 writing of one line on another in the receiv-
ing instrument; and a set of circuit making
contact points forming a part of a circuit
collateral to said energizing circuit, and auto-
matically held together by said ledge means
15 in its attracted position, whereby activity of
said electro-magnet is maintained after said
carriage return key is released, until said
cross circuit is closed.

9. In a telegraph transmitter, means for
20 transmitting code combinations of impulses
for printing operations, means for transmit-
ting a code combination of impulses for per-
forming a carriage return operation, and
means responsive to said last mentioned means
25 for positively rendering said first mentioned
means non-operative.

10. In a telegraph transmitter, means for
transmitting code combinations of impulses
for performing printing operations, means
30 for transmitting a code combination of im-
pulses for performing a carriage return op-
eration, means responsive to the last men-
tioned means for rendering said first men-
tioned means nonoperative, and means for
35 transmitting code combinations of impulses
for line feeding, said means also rendering
said first mentioned means operative again.

11. In a telegraph transmitter, a plurality
of key bars, means responsive to the opera-
40 tion of said bars for transmitting code com-
binations of printing impulses, a key bar,
means responsive thereto for transmitting a
carriage return combination of impulses, an-
other key bar, means responsive thereto for
45 transmitting a line feed code combination of
impulses, means operative in response to the
operation of said carriage return bar for ren-
dering said printing bars non-operative, said
means being operative in response to the op-
50 eration of said line feed bar for rendering
said printing bars again operative.

12. In a telegraph transmitter, a plural-
ity of key bars, a stunt key bar, means re-
sponsive to the operation of said stunt key
55 bar for rendering said plurality of key bars
non-operative, means for thereafter main-
taining said key bars in a non-operative con-
dition independently of said stunt bar, a sec-
ond stunt bar and means responsive to the
60 operation of said second stunt bar for ren-
dering said key bars operative.

13. A keyboard comprising a plurality of
key levers, means responsive to the operation
of said levers for transmitting code combi-
65 nations of impulses and means for positive-

ly rendering said key levers non-operative
for an indefinite period of time.

14. A key board comprising a plurality of
key levers, permutation means responsive to
the operation of said levers for transmitting
70 code combinations of impulses, means re-
sponsive to predetermined conditions for
positively rendering said levers non-oper-
ative and manually controlled means for
changing said condition to render said levers
75 operative.

15. In a telegraph transmitter, a plurality
of key levers, a tape, means responsive to the
operation of said key levers for perforating
80 said tape for transmitting code combinations
of impulses, means for locking said key bars
to prevent further perforation of said type
and manually controlled means for releasing
said key levers for operation.

16. A key board comprising a plurality of
key levers, a locking bar having a plurality
of positions in one of which said type key
levers are held from operation, and means
responsive to a partial operation of one of
90 said levers for operating said locking bar to
said one position to hold said other key levers
from operating and spring means for main-
taining said bar in operative position.

17. A key board comprising a plurality
of transmitter levers, a lock bar having a
95 plurality of positions, in one of which said
levers are locked from operation, and a cam
member on said lock bar cooperating with
one of said levers whereby said lock bar is
moved to lock said other bars in response to
100 the partial operation of said lever.

18. In a telegraph transmitter, a plurality
of transmitter levers, a lock bar having a plu-
rality of positions in one of which said levers
are locked from operation, a cam member on
105 said lock bar cooperating with one of said
levers whereby said lock bar is moved to lock
said other bars in response to the partial op-
eration of said lever, a second cam on said
lock bar cooperating with another of said
110 levers whereby said lock bar is moved to re-
lease said levers in response to the partial
operation of said second lever.

19. A keyboard, comprising a plurality of
key levers, means for transmitting telegraph
signals controlled by said key levers, a lock-
ing bar mounted on said keyboard having a
plurality of positions, and means for moving
said locking bar longitudinally to one of said
positions to lock said levers against opera-
115 tions, said locking bar being operable to an-
other of its positions to release said levers for
operation.

20. A keyboard, comprising a plurality of
key levers for transmitting telegraph signals
controlled by said key levers, a locking bar
having a ledge mounted under said key levers,
said locking bar having notches cut therein
and being movable to a plurality of positions,
in one of which positions said notches are
125 130

under said key levers whereby said key levers are free to operate and in another of said positions said bar presents its ledge under said key levers whereby said levers are locked from operation.

5 21. A keyboard comprising a plurality of key levers, means for transmitting telegraph signals controlled by said key levers, a locking bar mounted on said key board, said locking bar having a plurality of normal positions in one of which said key levers are locked from operation, in the other of which said key levers are free to operate.

10 22. A key board comprising a plurality of levers, means controlled by said key levers, for transmitting code combinations of telegraph signals, a locking bar mounted in operative relation with said key levers, said locking bar having a plurality of positions in one of which said key levers are locked from operation and in another of which said levers are released for operation and a key lever in operative relation with said locking bar for operating it to one of its positions.

15 23. A key board comprising a plurality of levers, means controlled by said key levers for transmitting code combinations of telegraph signals, a locking bar mounted in operative relation with said key levers, said locking bar having a plurality of positions in one of which said levers are locked from operation and in another of which said levers are released for operation and means including certain of said key levers for directly controlling the movement of said locking bar to its plurality of positions.

20 24. A key board comprising a plurality of key levers, means controlled by said key levers for transmitting code combinations of signals, a locking bar mounted in operative relation with said key levers, having a plurality of normal positions, manually controlled means for operating said locking bar to one of its positions, for locking said key levers from operation and manually controlled means for operating said locking bar to another one of its positions, for releasing said key levers for operation.

25 25. A key board, comprising a plurality of key levers, means controlled by said key levers for transmitting code combinations of impulses, means responsive to a predetermined condition obtained in accordance with code combinations of impulses transmitted for rendering a lever non-operative, means operative in accordance with code combinations of impulses transmitted for changing said condition and means responsive to said change in condition for rendering said lever operative again.

30 26. A signalling system, a key board comprising a plurality of key levers, means responsive to operation of said levers for transmitting code combinations of impulses and locking means associated with said key levers

for positively rendering said key levers non-operative for an indefinite period of time.

27. A key board comprising a plurality of key levers, permutation means responsive to the operation of said levers for transmitting code combinations of impulses and latching means in operative relation with said key levers responsive to predetermined conditions for positively rendering said levers non-operative and manually controlled means for changing said conditions to render said levers operative.

30 28. In a telegraph transmitter, a plurality of key levers, a tape, means responsive to the operation of said key levers for perforating said tape for transmitting code combinations of impulses, mechanical locking means in operative relation with said key levers for locking said key bars to prevent further perforations of said tape and manually controlled means for releasing said key levers for operation.

In testimony whereof, I have hereunto set my hand on this the 12th day of June, 1926,

A. D.

95 WILLIAM E. HARDING.
